FUEL BURNER CONTROL SYSTEM

Du Wayne J. Peterson, Chicago, Ill., assignor to
Minneapolis-Honeywell Regulator Company,
Minneapolis, Minn., a corporation of Delaware.

Application March 17, 1937, Serial No. 131,363

5 Claims. (Cl. 158—42.1)

The present invention relates to a fuel burner control system and more particularly to one adapted for the control of a burner located in a place where it is likely to be subjected to flood conditions.

There are numerous residential areas in which the basements are so located that they are periodically flooded. The fuel burning equipment for heating the residence is usually located in the basement and when a flood does occur the fuel burner is liable to be extinguished. Where some automatic fuel feeding means is provided, the operation of the fuel feeding means is apt to continue after the extinguishment of the burner. This is a serious matter with any type of fuel. Even in the case of a solid fuel such as coal, it is not desirable to have a continuous feeding of the fuel after the fire has been extinguished. The extinguishment of the burner presents particular difficulties, however, when the fuel is a fluid fuel such as gas. In this case, the burner is extinguished but the gas continues to bubble through the water filling the basement with dangerous fumes. While automatic fuel feeding apparatus is quite commonly provided with some means for stopping the feeding of the fuel upon extinguishment of the burner, such means often becomes inoperative when immersed in water. Thus, in the case of a safety pilot switch which is opened upon the extinguishment of combustion, the subjecting of the switch to water will short the contacts and cause the circuit controlled thereby to be closed even though the pilot is extinguished.

An object of the present invention is to provide a control system for a fuel burner located where flooded conditions may occur, having a float actuated means for causing the supply of fuel to the burner to be interrupted upon the presence of liquid at a level sufficiently high to affect operation of the burner.

A further object of the present invention is to provide a control system for a fuel burner employing electrically operated fuel feeding controlling means operative only when energized to cause fuel to be fed to the burner, which has a normally closed switch in the energized circuit of the fuel feed controlling means and a float for moving the switch to open position upon liquid rising sufficiently high to affect operation of the burner.

A further object of the present invention is to provide a control system of the type previously discussed in which the switch is a snap action switch and in which manual resetting means is

provided for moving the switch back to circuit closed position after having been moved to circuit open position by the float.

Other objects of the invention will be apparent from a consideration of the accompanying specification, claims and drawing.

For a more complete understanding of the present invention, reference is made to the accompanying drawing in which

Figure 1 is a schematic view of my improved fuel burner control system, and in which

Figure 2 is a view partly in section of a float switch employed in the burner control system of the present invention.

Referring to Figure 1 of the drawing, a conventional furnace is indicated by the reference numeral 10. This furnace may be of any well known type, being shown for purposes of illustration as a warm air furnace, having ducts 11 leading to rooms which are to be heated. A gas burner 14 is located within the furnace. The gas burner is supplied with gas through a pipe 15 in which is interposed a valve 16. A pilot burner 17 is located adjacent to the main gas burner 14 and is supplied with gas from pipe 15 at a point 25 ahead of the valve 16.

The valve 16 is provided with an operating unit 17. This operating unit is of an electrical type and preferably of a type referred to commonly as a "stalled motor" type. This type of operating unit for a valve is shown in the patent to Paul F. Shivers No. 1,678,202 of July 24, 1928. In this type of device, the valve is biased towards closed position and the motor moves the valve against this bias to open position and maintains it in open position so long as the motor is energized. Upon deenergization of the motor, the biasing means returns the valve to closed position. It is to be understood that any type of electrically operated fuel feed controlling means may be employed, however, in lieu of the assembly consisting of valve 16 and operating unit 17.

A room thermostat or other automatic control device is employed to control the energization of the valve operator 17. In the drawing, a room thermostat has been shown and is indicated by the reference numeral 20. This thermostat consists of a bimetallic element 21 to which is connected a contact arm 22 adapted to engage with a contact 23. A magnet 24 is located in proximity to arm 22 and is adapted to exert a biasing effect upon the arm. The bimetallic element 21 is so disposed that upon a decrease in temperature, contact arm 22 is moved into engagement with contact 23 and upon an increase in tempera- 55

ture, the opposite action takes place. The effect of the magnet 24 is to cause contact arm 22 to move into engagement with contact 23 at a different temperature than that at which it moves 5 away from contact 23.

Transformer 30 is employed for supplying energy for operation of the system. The transformer 30 comprises a line voltage primary 31 and a low voltage secondary 32. The line voltage 10 primary 31 is connected to two line wires 33 and 34.

The float switch which, as has been previously indicated, operates to insure the closing of the valve upon flood conditions is indicated generally 15 by the reference numeral 40. This float switch is shown in detail in Figure 2. The float switch is contained in a housing having an enlarged portion 41 constituting its base and acting as a float chamber, an elongated tubular portion 42 20 extending upwardly from the enlarged portion, and a switch casing 43 located on top of the tubular portion 42. Located within the switch casing 43 is a mercury switch generally indicated by the reference numeral 45. The mercury switch 25 is of the conventional type having two electrodes at one end and a mercury globule, which, upon tilting of the switch, moves into and out of bridging engagement with these electrodes. The mercury switch is mounted upon a support 46 30 to which is attached a clip 47 pivoted at 48 to the casing 43. The pivot point 48 is located in line with the center of gravity of the switch, exclusive of the mercury, so that the mercury acts to hold the switch in either extreme position 35 to which it is moved. The two electrodes of the mercury switch 46 are connected to two terminals 49 and 50 which are adapted to have conductors secured thereto. The tubular portion 42 is sufficiently long that switch 45 will be above the 40 highest level to which the flood water will rise.

A rod 52 extends through the tubular portion 42 of the housing of float switch 40, being guided for longitudinal movement therethrough. This rod 45 extends clear to the bottom of the housing and is adapted to rest upon the floor or other similar supporting surface. The rod extends at its upper end into engagement with the switch support 46. The rod 52 is so aligned that it engages with the switch support at a point to 50 the right of the pivot point 48 so that upon upward movement thereof the switch 45 is tilted in a counter-clockwise direction. Supported on the rod 52 is a float 54 which may be of any suitable material such as cork. This float 54 55 is held in position on the rod 52 by nuts 55 and 56 or other similar fastening means. The enlarged portion 41 of the float switch housing is provided with slots 57 to permit entrance of liquid to the interior of the float chamber.

If the float 54 becomes surrounded with water, it raises and moves rod 52 upwardly to cause counter-clockwise movement of switch 45. When switch 45 passes its horizontal position, the effect 60 of the mercury globule is to cause it to rapidly rotate in counter-clockwise direction. The movement of the mercury globule away from the electrodes breaks the circuit controlled by the switch. In order to provide means for limiting the movement of the switch 45 in the direction of its open circuit position and to provide for readily moving the switch back to its circuit closed position, a rod 60 extends through the casing 43. This rod 60 is provided at its outer end with a push-button 61. A spring 62 is interposed be-

tween the push-button 61 and the switch casing 43 and serves to bias rod 60 outwardly. A collar 63 is secured to rod 60 and serves to limit the outward movement of the rod. The rod 60 is so positioned that upon counter-clockwise movement of switch support 46, the right end of the support will engage the rod 60. When it is desired to reclose the switch 45, all that is necessary to do is to push push-button 61 and the switch 45 is rotated in a clockwise direction to again assume the closed position shown in the drawing.

The mounting of the switch 45 so that the same remains in either circuit open or circuit closed position, depending upon which position it is moved to, is highly desirable inasmuch as it would not be advantageous to have the switch moved back to closed position until it was assured that conditions were such that operation of the burner was again desirable. With the arrangement shown and described, it is assured that switch 45 after having once been opened will not be reclosed until the manual operation of pushing push-button 61 has been performed.

Referring again to Figure 1, it will be noted that one terminal of the secondary 32 is connected to the switch terminal 49 through conductor 65. Switch terminal 50 is connected by conductor 66 to one terminal of the valve operator 17. A conductor 67 connects the other terminal of the valve operator to the bimetallic element 21. A contact 23 of the thermostat 20 is connected by conductor 68 to the other terminal of secondary 32.

Operation

Since the switch 45 is normally closed, terminals 49 and 50 are normally connected through the switch. Accordingly, whenever the temperature falls to a value wherein thermostatic switch arm 22 is moved into engagement with contact 23, a circuit is established to the valve operator 17 as follows: from the upper terminal of secondary 32, through conductor 68, contact 23, contact arm 22, bimetallic element 21, conductor 67, valve operator 17, conductor 66, switch 40, and conductor 65 to the other terminal of secondary 32. The energization of the valve operator by the establishment of the above traced circuit causes valve 16 to be moved to open position against the action of its biasing means, in the manner previously explained.

Let it be assumed that water or other liquid enters the room in which the furnace 10 is located. This room, of course, would normally be the basement. The water will enter the inside of the base portion 41 constituting the float switch housing through the openings 51 and will cause the float 54 to rise by reason of the buoyant action of the liquid. The rising of float 54 will cause upward movement of rod 52 so as to tilt the mercury switch 45 sufficiently to cause it to snap over center. Since switch 45 is in series with the valve operator, the energizing circuit thereto, if established, will be interrupted causing the valve to move to closed position. If the energizing circuit is not established, it will be assured that the valve will not be opened upon a call for heat.

Due to the fact that the switch flops or snaps over center, it is assured that the valve will remain closed until such time as an operator manually moves the switch 45 to closed position by pushing push-button 61. In this way, it is assured that if the water has in any way damaged

the heating equipment, the valve will not be opened as soon as the water has subsided.

It will be seen that the present invention provides a fuel burner control system in which it is assured that the supplying of fuel to the burner will be interrupted upon liquid rising to a level which would affect operation of the burner. This moreover is done through a float actuated device which is positive and direct. Moreover, it is seen that the switch forming a portion of my apparatus is located at a height sufficiently high that the flood waters will not reach the same. In this manner, it is assured that regardless of the extent to which the basement is flooded, the switch will always function to open the circuit to the operator of the fuel feed controlling means.

While I have shown a specific embodiment of my invention, it is to be understood that this is for purposes of illustration only and that my invention is to be limited only by the scope of the appended claims.

I claim as my invention:

1. In a gas control system, in combination, a device for controlling a flow of gas, said device being located in an enclosure susceptible to becoming flooded and thereby indicating flooded conditions in the vicinity of the enclosure, said gas being of a type employed in systems of such a nature that exposure of the systems to flooded conditions may create a dangerous hazard, a flood protection safety device comprising means responsive to rising flooding liquid operable to cause interruption of the flow of gas while the flooding liquid is at or above a predetermined level in said enclosure.

2. In a gas control system, in combination, a device for controlling a flow of gas, said device being located in an enclosure susceptible to becoming flooded and thereby indicating flooded conditions in the vicinity of the enclosure, said gas being of a type employed in systems of such a nature that exposure of the systems to flooded conditions may create a dangerous hazard, and a flood protection safety system comprising an electric valve and means responsive to rising flooding liquid operable to cause interruption of the flow of gas while the flooding liquid is at or above a predetermined level in said enclosure,

said last means including a circuit controlling said valve and circuit interrupting means located at a level above the normal rise of flooding liquid.

3. In a heating system for a building, in combination, means forming a combustion chamber in the basement of the building, means for burning gaseous fuel in said combustion chamber, said basement being susceptible to becoming flooded, means for normally controlling a supply of gaseous fuel to the fuel burning means, and means responsive to the presence of flooding liquid in said basement for interrupting supply of fuel to said fuel burning means while the liquid is at or above a predetermined level in said basement.

4. In a control system for a gaseous fuel in combination a burner located within an enclosure susceptible to becoming flooded, means for normally controlling the supply of fuel to the burner comprising means for forming an electric circuit, said fuel supply means admitting fuel to said burner when said circuit is completed, means responsive to the presence of flooding liquid in said enclosure for interrupting said circuit to prevent admission of fuel to said burner while the liquid is at or above a given level, said last means being arranged to avoid having flooding liquid act thereon to close said circuit irrespective of the effect of flooding liquid on other portions of the circuit, and the presence of said flooding liquid characterizing a condition independent of burner operations.

5. In a control system for a gaseous fuel in combination a burner located within an enclosure susceptible to becoming flooded, means for normally controlling the supply of fuel to the burner comprising means for forming an electric circuit, said fuel supply means admitting fuel to said burner when said circuit is completed, and means responsive to the presence of flooding liquid characterizing a condition in said enclosure independent of burner operations for interrupting said circuit to prevent admission of fuel to said burner while the liquid is at or above a given level, said last means comprising a device movable by the flooding liquid and a switch situated so as to be above the level of the rise of flooding liquid.

DU WAYNE J. PETERSON.
